No. 866,703.

PATENTED SEPT. 24, 1907.

G. L. WILKINS.
CASEMENT WINDOW ADJUSTER.
APPLICATION FILED MAY 6, 1906.

UNITED STATES PATENT OFFICE.

GEORGE L. WILKINS, OF CHICAGO, ILLINOIS.

CASEMENT-WINDOW ADJUSTER.

No. 866,703.

Specification of Letters Patent.

Patented Sept. 24, 1907.

Application filed May 8, 1906. Serial No. 315,740.

To all whom it may concern:

Be it known that I, GEORGE L. WILKINS, a citizen of the United States, residing at Chicago, in the county of Cook and State of Illinois, have invented a certain 5 new and useful Improvement in Casement Window Adjusters, of which the following is a specification.

My invention relates to mechanisms for operating hinged windows, more especially casement windows but is also well adapted for operating transoms and 10 other interior windows.

The general object of the invention is to provide simple and effective means for operating a window from a point inside of an inner window or screen.

A more specific object is to provide means whereby 15 a window screen may be mounted in the casement inside of the window without interfering with the operation of the adjusting device, and to so construct the parts that the screen frame may fit over the fulcrum block of the adjuster and the fulcrum block of the adjuster may fit over the operating lever closely enough 20 to prevent the entrance of mosquitos, flies and other insects.

I attain my objects by the mechanism illustrated in the accompanying drawings in which:

25 Figure 1 is a general front view showing the parts assembled. Fig. 2 is a horizontal sectional view illustrating the operation of the parts. Fig. 3 is a vertical sectional view taken on line 3—3 Fig. 2; and Fig. 4 is a horizontal sectional view taken on line 4—4 Fig. 1.

30 Similar letters refer to similar parts throughout the several views.

The form of device here illustrated is for operating casement windows; and in the drawings *a* represents the window casing or casement which has a sill *a'* 35 and supports the window *b*, preferably by means of hinges *b'*.

The operating lever *c* is pivoted upon the fulcrum pin *d* in the housing or fulcrum block *e*, the portion of 40 said lever adjacent to said pin being cylindrical and concentric therewith. Said housing which is secured to the sill *a'* by means of screws or otherwise is so formed as to make close contact with the cylindrical portion of lever *c* without actually binding the same. The purpose in thus designing the parts is to render it 45 possible to permit the lever to be swung through a maximum are for operating the window and yet maintain close enough contact between the cylindrical fulcrum portion of the lever and the housing to effectually exclude insects.

50 Although the method of connecting the lever to the

window is not an essential feature of the invention, an advantageous form of connection is illustrated in Figs. 1 and 2 in which a guide bar *f* is attached to the window and is slotted for receiving the head or pin *c'* at the outer extremity of lever *c*. With this construction the head *c'* is slidably engaged within bar *f*, and the rotation of said lever about its fulcrum pin *d* will swing the window to various positions as desired. Although for the sake of simplicity I prefer a direct connection between the lever and the window as in the 60 illustration it is obvious that other connections such as compound levers or link motions might be employed.

A simple and convenient means for rotating the lever from a point inside of the housing *e* is afforded by the handle *c²* which in the present preferred design forms 65 an integral part of the lever.

In order to provide means for retaining the window in any desired position a retaining device is employed, and while such retaining device might assume various forms an advantageous one is best illustrated in Fig. 70 4. There the cylindrical fulcrum portion of the lever *c* has a series of notches *c³* adapted to receive the extremity of a detent *g* which is pivoted within the housing and is influenced by means of a spring *g¹* to remain in engagement with the lever. Said detent 75 is hand releasable by means of the projecting extremity *g²*.

An impenetrable member such as a second window or a window screen *h* is mounted within the casement inside of the window in such position as to be coincident with the plane of the housing or fulcrum block *e*. The screen frame is recessed at the bottom at *h'* in such manner as to closely fit over the housing *e*, and in order to facilitate the fitting of the screen frame to the housing it is desirable that said housing be rectangular in horizontal cross sections as shown in the drawings. It is also desirable that the width of the housing be approximately the same as the width of the screen frame as indicated in Fig. 2.

In operation, when the screen frame is lowered to 90 normal position as shown in Fig. 1 it makes such close contact around the edges of housing *e* as to prevent the passage of insects and similarly the housing makes contact with the cylindrical portion of lever *c*. When it is desired to open or close the window it is merely 95 necessary to release the detent *g* and by means of the handle *c²* swing lever *c* to the proper position. By this means the window may be swung to open, closed or intermediate positions without raising or removing the screen and without affording any apertures either 100

between the screen frame and the housing or between the housing and the operating lever through which insects may gain access to the building.

What I claim as new and desire to secure by Letters
5 Patent is:

A casement window adjuster comprising a block adapted to be secured to a window-sill, said block having an opening therethrough, a lever pivotally mounted in said opening, and constructed to practically close the same in

all positions of adjustment, one end of said lever serving 10 as an operating handle and the other end being adapted for connection to the window to be adjusted, and means mounted in said block for locking said lever in different positions of adjustment.

In witness whereof, I have hereunto subscribed my 15 name in the presence of two witnesses.

GEORGE L. WILKINS.

Witnesses:

HOWARD M. COX,
CLARA J. CHRISTOFFEL.
